UNITED STATES PATENT OFFICE.

THOMAS C. CHAPPELL AND EVERETT D. MOORE, OF BALTIMORE, MARYLAND;
SAID MOORE ASSIGNOR TO SAID CHAPPELL.

LETTER-BOX.

SPECIFICATION forming part of Letters Patent No. 400,299, dated March 26, 1889.

Application filed May 1, 1888. Serial No. 272,453. (No model.)

To all whom it may concern:

Be it known that we, THOMAS C. CHAPPELL and EVERETT D. MOORE, both citizens of the United States, and residents of the city of 5 Baltimore, in the State of Maryland, have invented certain new and useful Improvements in Letter-Boxes, of which the following is a full and exact specification, reference being had to the accompanying drawings, in which 10 similar letters of reference indicate similar parts.

Our invention relates to letter-boxes which may be used for all classes of mail-matter, both letters and packages.

15 In making a mail-box for packages it is necessary to provide means by which the necessarily-large opening provided as an entrance to the box should not, when opened, expose the interior in such a manner that 20 packages already in the box can be extracted either by the hand or by an instrument provided with a hook.

Our invention is designed to accomplish 25 this result by providing the box with a false bottom or diaphragm, which divides it into an upper and lower section. The upper section is used to receive the mail-matter and the lower one to store it until collected by the proper official, who has access to the storage-box in the same general manner as is now 30 used for letter-boxes.

The further features of our invention consist of mechanism by which the false bottom 35 is closed and locked before the entrance door or lid can be opened, in which condition it will remain while the door or cover is opened and closed again, and mechanism by which the door or cover when closed will be locked until the false bottom has been dropped so 40 as to deposit its mail-matter into the storage-box and raised and locked again.

In the drawings, Figure 1 is a front elevation of the entire box. Fig. 2 is a vertical section through the center of the box, with 45 lid raised, shown in dotted lines, and also changed position of other parts. Fig. 3 is a top view of box. Fig. 4 is a sectional detailed view showing internal mechanism. Fig. 5 is a side view of same. Fig. 6 is a 50 sectional detailed view showing working

parts in different positions. Fig. 7 is a plan view of working parts. Fig. 8 is a sectional front elevation showing a modification of working parts and extracting-door, the extraction-door being removed. Fig. 9 is a sectional side elevation of same. Fig. 10 is a view of top of box with cover removed.

A represents the sides or walls of the box, made, preferably, of cast-iron, and cast in one or more parts. The sides and back are preferably flat. The front is partially flat and partially semi-cylindrical.

B is the bottom, which may be cast integral with the sides or separated. It may also be made of any desired form. We have shown a 65 form which we prefer in Fig. 2, in which the bottom has a depression at or about the middle.

C is the extracting-door. (Shown in Figs. 1, 2, and 3.) In these figures it is shown as made 70 convex on the exterior and meeting similar-shaped projections on the sides of the box. This form has the advantage of giving greater storage capacity on the interior of the box. The form is not material, however, and we have 75 shown another form in Figs. 8 and 9.

D is the cover or entrance door of the box, which is the same in all of the figures, save 8, 9, and 10, in which it is shown with some modifications. The lid D is hinged to the side wall 80 of the box in any suitable way, and in Figs. 1, 2, 3, 4, 5, and 6 is constructed in the following manner: Referring to Figs. 4, 5, 6, and 7, the cover is made preferably of cast iron and cored so as to consist of a chamber or pocket 85 closed on all sides save the back. On the open side we place the hinges, and when the cover is secured to the box by them the open side of the cover is closed by resting against the back of the box. We construct the cover in 90 this way because it is desirable to cover the levers and catch, which operate on the inside of the lid and prevent them from being exposed when the lid is opened.

D' is a lever pivoted to the center of the 95 outside of the cover by the stud d, to one end of which it is secured. Said stud projects through the cover and is journaled in it, and to the other end of the stud is secured the lever D² in a right line with the lever D'. The 100

free end of the lever D' is turned downward and inward so as to form a hook, d^3 , which engages the edge of the cover, and also a projecting ledge, a' , on the top of the front wall 5 of the box. This ledge a' is in shape a section of a circle, and so long as the hook d^3 engages said ledge the cover of the box cannot be opened. So soon, however, as it passes the end of the ledge it may be. In this way we 10 insure a complete throw of the levers D' and D^2 , and hence a complete raising and locking of the false bottom before the cover of the box can be opened.

On the interior of the pocket or casing, at 15 a point opposite the stud d and on the right-hand side of it, looking from the front backward, is cast a lug or block, k , perforated with a square hole, k^2 , which extends through the casing also. Into this hole is fitted a square bolt, k^3 , which is turned into a right angle, as 20 shown in Fig. 4. The hole is horizontal, and when the cover of the box is closed or horizontal the free end of the bolt will be perpendicular. The upright end of the bolt bears 25 upon the side of the boss of levers D^2 around stud d . Said boss is made in the form of a cam, K —that is to say, with a swell on one side. The bolt k^3 is encircled by a spiral spring, k^4 , which bears upon the lug or block 30 k and upon the upright part of said bolt, thus keeping the bolt withdrawn from the hole k^2 as far as the boss of the lever D^2 and cam K will permit.

About midway of the height of the box or 35 at any desired distance from the top are hinged two pieces of board or flat metal, $E E$, of such a width that when drawn up to the horizontal they will form a complete diaphragm or false bottom to the box. To the 40 extremities of the sections $E E$ are attached chains $j j$, the other ends of which are secured to a sliding bar, J , which is held and slides in guides $j^3 j^3$, secured to the interior of the side wall of the box. To the upper end of this 45 slide J is secured a chain, F , which passes up and over a sheave, H , which turns on a pin set into the side wall of the box near the top and immediately above the guides $j^3 j^3$. Thence the chain F passes horizontally toward 50 the back of the box and around sheave G , which is in a horizontal position and turns upon a pin or stud set in a projecting bracket, which is also secured to the side of the inner wall of the box. Chain F thence passes horizontally across the rear of the box, still on the 55 interior, and is secured to the end of the lever D^2 . Over the mechanism just described is placed an inclosing shield or case, which consists of the cover a^2 and the vertical partition A' . This cover is secured to the interior wall of the box in any suitable way, and 60 in Figs. 4 and 6 the top a^2 serves as the bracket to which sheave G is secured. The vertical partition A' is perforated with a hole, 65 a^3 , in such position that when the cover D is closed it will stand opposite to the end of the

bolt k and form a keeper for said bolt, serving to lock the cover D and prevent its being opened. The sliding bar J at its upper end is perforated with a hole, j^1 , in which slides 70 the bolt j^2 having a collar, j^5 , a short distance from its end, and is encircled by a spiral spring, j^6 , by which it is pressed away from the sliding bar J as far as the vertical partition A' will permit. The other end of the 75 bolt j^2 rests against the interior of the vertical partition A' , (see Fig. 4,) and the end slides upon it as the bar J is raised and lowered. When the levers D' and D^2 are turned, the 80 chains F drawn, and the bar J raised, the bolt k^3 will be forced out of the hole or keeper a^3 by the spring k^4 , in consequence of the cam K being turned so as to permit it, and when the bolt j^2 , as the bar J rises, reaches the hole 85 a^3 , it being in a vertical line therewith, the spring j^6 will force the bolt j^2 into said hole and lock the false bottom $E E$ in a horizontal position. When this has been accomplished, the hook d^3 on the end of the lever D' will have passed the end of the ledge a' , and the 90 cover D may now be raised for the admission of mail-matter.

It is desirable that the cover should always be left in a position in which, if released, it would at once fall and close the box. One 95 form of device for accomplishing this is shown in Figs. 2, 4, and 5. The bar L is made with an anchor or cross-piece at one end, and is fitted into a staple or keeper, l , which is secured to the side of the vertical partition A' , 100 just below the level of the inside of the cover. The upper end of the bar is perforated with a hole through which presses the bolt k^2 , which serves to unite the bar to the cover. This bar is of such a length that when the cover D is 105 raised the bar will permit it to be opened sufficiently to place mail-matter in the box, but not to pass beyond the perpendicular, and when released the cover will fall by gravity, drawn down also by the weight of the 110 bar. Other means of accomplishing this result may be devised.

The operation of the device is as follows: When it is desired to open the box to deposit mail-matter, the lever D' is turned to the 115 right until the hook d^3 has become disengaged from the ledge a' . The turning of the lever D' also turns D^2 and draws the chain F , and as the cam K is turned permits the spring k^4 to withdraw the bolt k^3 from the hole a^3 , thus 120 unlocking the box. As the chain F rises the bar J will be drawn up and the false bottom $E E$ with it. When bar J rises high enough, the bolt j^2 will spring into the hole a^3 and lock the false bottom in a horizontal position. 125 Mail-matter is now deposited, the cover closed again, and the lever D' turned back to its normal position, or it may be provided with a spring or weight to draw it back automatically. As it returns to its central position its 130 cam K will force the bolt k^3 into hole a^3 and bolt j^2 out of said hole. The release of bolt j^2

will release bar J and let the false bottom E E drop and deliver its mail-matter in the storage-chamber.

In Figs. 8, 9, and 10 we have shown a modified form of construction for carrying out our invention. In this modification the lever D', instead of being pivoted to the cover, is a lever of the second kind, and is secured at one end to the rear wall of the box, and is attached directly to the sliding bar J, which is extended upward and is beveled on its end and inclined toward the partition A'. Secured to the bar J is a projection, X. A bar, L, is pivoted to the under side of the cover D, and enters the cavity or space between the wall A and the partition-wall A', which is open at the top when the cover is closed. Said bar L is also beveled on its end inclined toward the exterior wall of the box and also has a projection, y, secured to it.

Set in a hole in the partition A', which is a little above the level of the end of the bar J when raised, is a bolt, b, held in a desired position of extension by a spring, w, and projecting into the interspace between the wall A and the partition A'. Set in a hole in the wall A, which is a little below the level of the end of the bar L when the cover is closed, is a bolt, b', held in place and at a desired point of extension by the spring b². The projection X on bar J is so placed that when J is at its highest point said collar will pass above and engage the bolt b' if it is sufficiently extended and sustain the false bottom E E in a horizontal position. The projection y on bar L is so placed that when the cover D is closed the collar will be below the level of the bolt b, and when the same is sufficiently extended it will engage said projection, lock the cover, and prevent its being opened. A spring is provided on the under side of the cover or edge of the box to raise the cover a short distance when unlocked, thus permitting the instant locking of the false bottom. The operation of the device is as follows: When the lever D is raised, the end of the bar J will strike the spring w, throw back the bolt b, and release the bar L. The spring in the cover or on the edge of the box will raise the cover and rod sufficiently to release the spring b² and bolt b' and cause said bolt to engage the projection X on bar J and lock the false bottom E E. Mail-matter is then deposited and the cover D closed. The bar L strikes the spring b², withdraws the bolt b', and releases bar J and false bottom E E. Also, at the same time as spring w is released, bolt b will shoot out and engage projection y of bar L and lock the cover.

Having thus described our invention, what we claim, and desire to secure by Letters Patent, is—

1. A box for the reception of mail-matter, in combination with a cover provided with locking mechanism, and a false bottom also provided with locking mechanism, and means

for unlocking the cover and closing and locking the false bottom simultaneously.

2. A box for the reception of mail-matter, in combination with a cover provided with locking mechanism, a false bottom also provided with locking mechanism, and means for locking the cover and unlocking the false bottom simultaneously.

3. A box for the reception of mail-matter, in combination with a cover which is provided with locking mechanism, and a false bottom also provided with locking mechanism, and mechanism attached to the false bottom and controlling the locking mechanism of the cover and false bottom, whereby from the exterior of the box the false bottom may be closed and locked and the cover unlocked simultaneously, or the cover when closed may be locked and the false bottom unlocked and opened simultaneously.

4. A box for the reception of mail-matter, in combination with a cover which is provided with locking mechanism, and a false bottom also provided with locking mechanism, and a lever suitably pivoted to a part of the box attached to the false bottom and controlling the locking mechanism of the cover and false bottom, whereby from the exterior of the box the false bottom may be closed and locked and the cover unlocked simultaneously, or the cover when closed may be locked and the false bottom unlocked and opened simultaneously.

5. A box for the reception of mail-matter, in combination with a cover and a false bottom and a lever suitably pivoted to a part of the box and attached to the false bottom, and a locking mechanism for the false bottom which operates automatically to lock the false bottom when it is raised and closed, and a locking mechanism for the cover controlled by the lever by which the false bottom is raised, in such a manner that the cover will be unlocked when the lever has raised the false bottom and its locking mechanism has locked it, substantially as described.

6. A box for the reception of mail-matter, in combination with a cover provided with locking mechanism, and a false bottom also provided with locking mechanism, and means for locking the false bottom by mechanism which operates to unlock the cover.

7. A box for the reception of mail-matter, in combination with a cover provided with locking mechanism, and a false bottom also provided with locking mechanism, with means for locking the false bottom operated by the same mechanism which unlocks the top.

8. A box for the reception of mail-matter, in combination with a cover provided with locking mechanism, and a false bottom also provided with locking mechanism, and means for locking the cover when closed by mechanism which operates to unlock the false bottom.

9. A box for the reception of mail-matter, in combination with a cover provided with

locking mechanism, and a false bottom also provided with locking mechanism, and means for locking the cover when closed operated by the same mechanism which unlocks the false bottom.

10. A box for the reception of mail-matter, in combination with a cover, and provided with locking mechanism which consists of a rod secured thereto, and a bolt suitably located on the interior of the box in position to engage said rod and lock the cover, and a false bottom also provided with a rod secured thereto and operating within the box and connected with a bolt engaging said rod, whereby the false bottom when closed may be locked, and means connected to the false-bottom rod whereby the false bottom may be raised and locked, and means secured to or operated by the false-bottom rod whereby the locking mechanism of the cover will be released when the false bottom has been raised and locked, substantially as described.

11. A box for the reception of mail-matter, in combination with a cover which is provided with locking mechanism, which consists of a rod secured to the cover, and a bolt suitably mounted on the interior of the box in position to engage the hole in or offset upon said rod, whereby the cover may be locked, and a false bottom also provided with a rod, and a bolt suitably located on the interior of the box in position to engage a hole in or projection upon said rod, whereby the false bottom may be

locked when closed and a lever pivoted to a suitable part of the box and attached to the false bottom, and mechanism operated by said lever whereby, when the false bottom is closed and locked, the cover will be unlocked.

12. A box for the reception of mail-matter, in combination with a false bottom provided with a rod which engages a bolt suitably located within the box to engage a hole in or projection upon said rod and lock the false bottom when closed, a cover for said box also provided with a rod, and the bolt suitably located within said box to engage a hole in or projection upon said rod, and means operated by the cover whereby the false bottom will be unlocked and opened when the cover is closed and locked.

13. A box for the reception of mail-matter, having an opening in the bottom and a door hinged to one side of said opening, the two opposite sides of the box between which the door swings extending below the level of the other two sides and being provided with devices to limit the fall of the door, substantially as described.

In testimony whereof we affix our signatures in presence of two witnesses.
